UNITED STATES PATENT OFFICE.

JOSEPH H. BOURGON, OF DETROIT, MICHIGAN, ASSIGNOR TO THE STUDEBAKER CORPORATION, OF SOUTH BEND, INDIANA, A CORPORATION OF NEW JERSEY.

LATCH.

Application filed June 7, 1924. Serial No. 718,855.

This invention relates to latches such as are used for holding a movable part to a stationary part and has for its principal object the providing of such a latch that includes certain novel features which render it simple in construction and efficient in operation.

Another object is to provide such a latch which will act to draw the parts together when in operative position and will prevent the same from rattling.

A further object is to provide such a latch which comprises a longitudinally screw-operated bolt suitably prevented from turning, and operated by means of a handle which is provided with means for preventing the same from inadvertently turning.

The above being among the objects of the present invention, the same consists of certain features of construction and combination of parts to be hereinafter described, with reference to the accompanying drawing, and then claimed, having the above and other objects in view.

In the drawing which illustrates a suitable embodiment of the present invention, and in which like numerals refer to like parts throughout the several views,

Figure 1 is a side view of the latch and associated parts in operative position, certain of the parts being shown in section and broken away to more clearly show the invention.

Figure 2 is a perspective view of the bolt guide member.

Figure 3 is a perspective view of the bolt.

Figure 4 is a perspective view of the keeper.

Figure 5 is a perspective view of the collar which guides and supports the handle.

Figure 6 is a perspective view of the washer used to prevent the handle from inadvertently turning.

Figure 7 is a perspective view of a fragment of an automobile showing the adaptation of the present invention thereto.

Figure 8 is a section taken on the line 8-8 of Figure 1.

For the purpose of illustration, a latch embodying the present invention is shown incorporated in an automobile 10 of the roadster type which is provided with a rear compartment 11 to which access is gained by lifting the cover 12 hinged at its forward upper edge 13 to the body of the automobile 10. The rear end of the cover 12 can be

lifted vertically upward from closed position about the hinged edge 13 in the operation of opening the cover, and the lower edge thereof is adapted to extend downwardly to a position substantially flush with the bottom of the body sill 14 when in closed position. As in the conventional constructions, the cover 12 is provided with a lateral flanged portion adapted to overlie the edge of the opening leading into the rear compartment 11, thereby to support the cover 12 and prevent rain or moisture from entering the rear compartment 11.

The bolt portion of the latch is positioned in the vertically disposed free edge portion of the cover 12 and consists essentially of a non-rotating hook-end bolt 15 longitudinally movable perpendicular to the plane of the adjacent part of the cover 12 by means of a rotatable but longitudinally immovable handle 16, the shank of which is axially co-incident therewith and which is internally screw threaded to receive the threaded shank of the bolt 15 thereby to cause longitudinal movement thereof. The hook end 17 of the bolt 15 is adapted to engage the reversed hook end 18 of the keeper member 19 secured to the upper face of the body sill 14.

The bolt 15 and handle 16 are supported by the cover frame member 20 in the following manner. An opening 21 is provided in the frame member 20, and projecting into the opening 21 is the collar member 22 whose outer edge is provided with a laterally extending flange 23 adapted to overlie the edges of the opening 21 and be secured to the cover thereby, and whose inner edge is provided with a plurality of notches 24. The shank of the handle 16 is received in the collar 22 and is of such a diameter as to loosely fit the same and is provided with a circumferential bead or flange 25 which is adapted to abut against the outer surface of the collar 22 and thus limit the inward movement of the handle 16. The shank of the handle 16, from a point adjacent the flange 25 and extending inwardly therefrom, is milled off to provide two flat surfaces as shown most clearly in section in Figure 8. Over this milled shank is placed the washer 26 whose central opening is formed to a shape corresponding to the shape of the milled portion of the shank and is prevented from turning relative to the shank thereby. The washer 26 is further

provided with projections 27 which are adapted to seat in the notches 24 in the inner edge of the collar 22. A spring 28 encircling the shank of the handle 16 is compressed between the washer 26 and the washer 29 the latter of which is held in place on the shank by the pin 30. It is evident that the spring 28 holds the handle 16 in place and tends to hold the projections 27 in the notches 24 and thereby prevent inadvertent turning of the handle 16 or rattling of the same. When pressure is applied to the handle 16 to turn the same the projections 27 are forced out of the notches 24 against the pressure of the spring 28 and the handle is then capable of being turned as desired.

On the rear face of the frame member 20 is secured a plate 31 provided with an opening 32 in alignment with the shank of the handle 16; the metal punched out to form the opening being bent over on the lower edge to form a bearing surface for the lower surface of the bolt 15. Secured to the plate 31 by welding or other suitable means is a guide member 33 projecting out therefrom parallel to the bolt 15 and is provided with a slot 34, its lower surface forming a bearing surface at the upper edge of the opening 32 for the upper surface of the bolt 15. A projection or fin 35 projecting upwardly from the end of the bolt 15 is received in and guided by the slot 34 and the bolt 15 is prevented from rotative movement thereby. The keeper member 19 is provided with an upstanding projection 36 for limiting the inward or loosening movement of the bolt 15 in order to prevent the same from being unscrewed out of engagement with the handle 16. The hook end 17 of the bolt 15 and the hook 18 of the keeper member 19 are preferably formed to provide engaging cam-like surfaces so that when the handle 16 is turned to draw the two surfaces into engagement, the cover 12 will be drawn downwardly as well as inwardly against the body 10 and will thereby hold the same securely in place and prevent rattling.

It is evident from the foregoing that the construction herein disclosed embodies a novel and efficient construction and although but one embodiment of the invention is shown and described I do not limit my invention to the same as it is evident that it is capable of certain formal changes and modifications without departing from the spirit or substance of the broad invention, the scope of which is commensurate with the appended claims.

What I claim is:—

1. In combination with a movable member and a stationary member, means for securing said movable member against movement comprising a keeper having a cam surface, a slidable bolt having a cam surface thereon engageable with said cam on said keeper,

means to prevent rotation of said bolt, a handle provided with an extending shank for threadably receiving said bolt, and means for preventing movement of said handle longitudinally of said movable member. 70

2. In combination with a stationary member and movable part, a keeper member secured to said stationary member; a bolt carried by said movable part, comprising a hoop portion for engaging said keeper member, a threaded extending portion, and means for preventing rotation thereof; a handle provided with an extending shank for threadably receiving said bolt; and 80 means for preventing movement of said handle longitudinally of said shank.

3. A latch comprising a keeper member having a hook portion; a longitudinally movable bolt having a hook portion, a threaded shank, and a projection; a rotatable handle having a shank axially coincident with said bolt and provided with means for receiving the threaded shank of said bolt; a guide plate having a slot to receive the projection on said bolt and an opening to receive and support said bolt; and means for supporting and preventing longitudinal displacement of said handle. 90

4. Means for securing a movable member to a stationary part, comprising a keeper member having a hook portion secured to said stationary part; a non-rotatable longitudinally movable bolt having a hook portion to engage the hook portion of said keeper, and a threaded shank; an axially stationary rotatable handle provided with means for axially receiving said threaded shank of said bolt, said handle having a circumferential flange thereon; a collar surrounding said handle and secured to said movable member and provided with notches in one end thereof; a washer non-rotatably mounted on said handle having projections to engage the projections on said collar; and resilient means for holding said circumferential flange and said washer against said collar. 100

5. In combination with the rear compartment of an automobile body and a hinged cover therefor, of a keeper member provided with a cam portion secured to said body adjacent the free edge of said cover; a bolt provided with a cam portion; means for supporting said bolt at the free edge of said cover; means for preventing rotation of said bolt; and a rotatable, axially immovable handle provided with a shank threadably receiving said bolt for causing longitudinal movement thereof, said longitudinal movement of said bolt being provided to cause engagement of said cam portion with said cam portion on said keeper member and to draw the free edge of said cover downwardly and inwardly. 115 120 125 130

6. A latch comprising a longitudinally movable bolt having a hook end provided with a cam face, means for preventing rotation of said bolt, a rotatable handle provided with a shank for threadably receiving said bolt, means for preventing axial movement of said handle, a keeper member provided with a cam face for engagement with

the cam face of said bolt and further provided with means for limiting the movement 10 of the cam face of said bolt away from the cam face of said keeper member.

Signed by me at Detroit, Michigan, U. S. A., this 2nd day of June, 1924.

JOSEPH H. BOURGON.

6. A latch comprising a longitudinally movable bolt having a hook end provided with a cam face, means for preventing rotation of said bolt, a rotatable handle provided with a shank for threadably receiving said bolt, means for preventing axial movement of said handle, a keeper member provided with a cam face for engagement with the cam face of said bolt and further provided with means for limiting the movement 10 of the cam face of said bolt away from the cam face of said keeper member.
- Signed by me at Detroit, Michigan, U. S. A., this 2nd day of June, 1924.

JOSEPH H. BOURGON.

Certificate of Correction.

Patent No. 1,616,106, granted February 1, 1927, to

JOSEPH H. BOURGON.

It is hereby certified that error appears in the printed specification of the above-mentioned patent requiring correction as follows: Page 2, line 76, claim 2, for the word "hoop" read *hook*; and that the said Letters Patent should be read with this correction therein that the same may conform to the record of the case in the Patent Office.

Signed and sealed this 1st day of March, A. D. 1927.

[*initials*.]

M. J. MOORE,
Acting Commissioner of Patents.

Certificate of Correction.
